UNITED STATES PATENT OFFICE.

ARTHUR HENRY GIBSON, OF EASTON, PENNSYLVANIA, ASSIGNOR TO INGERSOLL-RAND COMPANY, OF NEW YORK, N. Y., A CORPORATION OF NEW JERSEY.

PULSATOR FOR PULSATORY TOOLS.

1,151,936.

Specification of Letters Patent.

Patented Aug. 31, 1915.

Application filed September 7, 1912. Serial No. 719,185.

To all whom it may concern:

Be it known that I, ARTHUR H. GIBSON, a subject of the King of Great Britain, residing at Easton, in the county of Northampton and State of Pennsylvania, have invented a certain new and useful Improvement in Pulsators for Pulsatory Tools, of which the following is a specification.

This invention relates to pulsators for use with percussive tools operated by pulsating columns of air and more particularly to a machine of this type adapted to run at high speed for use with tools of the hammer type.

15 Pulsators as at present constructed, cannot be run over a certain comparatively low speed, say five hundred reciprocations per minute, the vibrations at speeds above this being so great as to render the devices impractical.

20 The object of the present invention is to construct a pulsator which can be operated at twelve hundred reciprocations or over, a minute, and be directly connected with an electric motor, without the objectionable vibration accompanying the present designs. With this object in view I have devised a pulsator, a practical embodiment of which is shown in the accompanying drawings, in 25 which:

25 Figure 1 shows a vertical longitudinal section through the pulsator end, and Fig. 2 shows a similar horizontal section on the line II—II of Fig. 1.

30 The pulsator as shown comprises two cylinders 1—2 directly opposed in a horizontal line and slightly offset vertically. The inner portions 3—4 of each of the cylinders are of smaller diameters. In each cylinder are pistons 5—6 having a head sliding in the larger diameter portion of the cylinder and a smaller portion sliding in the inner portion of its cylinder. Immediately between the cylinders and in direct line with the pistons is a shaft 7 driven preferably directly from an electric motor (not shown). Driving means for reciprocating the pistons in opposite directions are operated from the shaft 7. As shown this 35 driving mechanism consists of connecting rods 8—9 pivotally mounted on cross pins 10—11 in the smaller portion of the piston, the connecting rods having at their inner ends circular straps 12—13 which surround 40 oppositely mounted circular eccentric cams

45—50 secured to the shaft 7. The form of driving mechanism is immaterial however, the essential feature being that the shaft is directly in line with the pistons.

55 The outer ends of each of the cylinders 60 serve as pulsating chambers, and are provided with pipes 16—17 which come together and lead by a single pipe 18 to the tool to be operated (not shown). The device as shown is designed for use with what 65 is known as a "one hose tool" and for this purpose the pipe 18 is the only connection needed. If however it is desired to convey air to both sides of the tool piston, a second pipe 19 can be attached to the space between 70 the cylinders in which the air is also alternately compressed and expanded. Under ordinary circumstances this opening is closed.

75 In order to provide air to build up and maintain pressure in the system, the annular pressure chambers formed by the shoulders of the pistons in the large diameter portions of the cylinders are used as a pumping means, air being taken in at the 80 outer end of the piston stroke through ports 20—21 and delivered to the other side of the pistons to the pulsating chambers by passages 22—23 which just bridge the pistons at the inner end of their stroke. 85

85 It is to be understood that the present showing and description discloses only one specified modification of my invention and other forms and modifications are included in the spirit and scope of the invention as 90 expressed in the claims.

95 What I claim is:

1. In a pulsator for pulsatory tools, two opposed cylinders, pistons in said cylinders having shoulders dividing each of said cylinders into two parts, one of said parts serving as a pulsating chamber and the other as pumping means for maintaining the pressure in the system, a shaft in line with said pistons and operative connections 100 between said shaft and pistons for reciprocating said pistons simultaneously in opposite directions.

105 2. In a pulsator for pulsatory tools, two opposed cylinders, pistons therein having shoulders dividing each of the cylinders into two parts, a pulsating chamber and an annular compression chamber, air inlet passages for said compression chambers, and discharge passages to said pulsating cham- 110

- bers, a shaft in line with said piston and operative connections between said shaft and pistons for reciprocating said pistons simultaneously in opposite directions.
- 5 3. In a pulsator for pulsatory tools, two opposed cylinders having larger diameter outer portions and communicating inner portions of smaller diameters, pistons having heads fitting said larger cylinder portions and smaller extensions fitting said inner cylinder portions, said larger cylinders and said smaller cylinders forming pulsat-
- 10

ing chambers of different volume, a shaft in line with said pistons, and operative connections between said shaft and said pistons for reciprocating the pistons in opposite directions.

In testimony whereof, I have hereunto set my hand.

ARTHUR HENRY GIBSON.
